UNITED STATES PATENT OFFICE.

ALFRED E. JOHNSON, OF RACINE, WISCONSIN.

SHOE-FASTENING MEANS.

1,236,308.

Specification of Letters Patent.

Patented Aug. 7, 1917.

Application filed December 2, 1916. Serial No. 134,656.

To all whom it may concern:

Be it known that I, ALFRED E. JOHNSON, a citizen of the United States, residing at Racine, in the county of Racine and State 5 of Wisconsin, have invented new and useful Improvements in Shoe-Fastening Means, of which the following is a specification.

This invention relates to improvements in shoe fastening means. 10 In carrying out my invention it is my purpose to entirely dispense with the ordinary method of fastening shoes by strings or buttons, and to substitute in lieu thereof hook members pivotally secured each adjacent one of the confronting edges of the top 15 of the shoe and engaging with a stud or button upon the opposite or second edge of the top of the said shoe, each of said hooks having included in its construction spring 20 resilient means whereby the confronting edges of the shoe top will be drawn toward each other and also whereby the desired amount of yieldability will be imparted to the shoe upper so that inconvenience in this respect 25 by the wearer will be overcome.

It is a still further object of the invention to produce a shoe fastening means which shall be of an extremely simple construction, easy to operate and effective in its said 30 operation, and one which will tend to add to the ornamentality of the shoe.

With the above and other objects in view the improvement resides in the construction, combination and arrangement of parts set 35 forth in the following specification and falling within the scope of the appended claim.

In the drawing:

Figure 1 is a view illustrating the application of the improvement,

Fig. 2 is a perspective view of the improvement detached, and

Fig. 3 is a sectional view taken in a line with the longitudinal plane of one of the fastening means.

Referring now to the drawing in detail, the numeral 1 designates the upper of an ordinary shoe. In the present instance the upper 1, adjacent the confronting edges thereof, is provided with a series of spaced button or stud members 2—2 arranged in oppositely disposed pairs. To the shank of

one of the series of buttons 2 I connect an eye 3 formed upon one end of my improved fastening members 4. The opposite end of the fastener member is formed with a hook 55 5 which is adapted to engage with the shank of the button 2 diametrically opposite that to which the eye is pivotally secured. The hooked end 4 is formed with an angular extension providing a lever 6 whereby the 60 device may be operated. The body of the fastening member, between the hook and eye, may be, and preferably is thickened as indicated by the numerals 7—7, and formed between the said members 7 is a substantially 65 S-shaped spring 8. The body to the opposite sides of the spring is practically non-yieldable, but the spring 8 permits of a yielding motion being imparted to the device between the ends thereof either longitudinally or laterally, as will, it is thought, be readily understood.

The device is preferably constructed from a suitable piece of spring material, and while it is obvious that the eye 3 thereof 75 may be secured to one of the edges of the shoe upper in other manners than that described, it is thought that by providing two sets of buttons or studs the artistic appearance of the shoe upper will be increased. It 80 is, of course, also to be understood that the spring 8 of the device may be of a different shape from that illustrated in the drawing.

From the above description, taken in connection with the accompanying drawing, the 85 simplicity of the device, as well as the advantages thereof will, it is thought, be perfectly apparent to those skilled in the art to which such invention appertains without further detailed description.

Having thus described the invention, what I claim is:

A shoe fastener constructed from a single piece of material having one of its ends formed with an eye, its opposite end formed 95 with a hook, a handle projecting angularly from the hook, said fastener being thickened from the ends thereof and being centrally reduced and said reduced portion being formed to comprise a spring.

In testimony whereof I affix my signature.

ALFRED E. JOHNSON.
